UNITED STATES PATENT OFFICE.

MARTIN STIELER, OF CHICAGO, ILLINOIS.

CONCRETE FORM.

Application filed May 5, 1924. Serial No. 710,984.

To all whom it may concern:

Be it known that I, MARTIN STIELER, a citizen of the United States, and a resident of the city of Chicago, county of Cook, and 5 State of Illinois, have invented certain new and useful Improvements in Concrete Forms, of which the following is a specification.

My invention relates to concrete forms, 10 and more particularly to forms for making concrete chimneys. The object of the invention is to provide an improved construction of this kind arranged to expedite the building of concrete chimneys and structures of 15 various forms and shapes; and also to provide improved means for readily placing and adjusting the form members in position.

Other objects will appear hereinafter.

20 The invention consists in the combinations and arrangements of parts hereinafter described and claimed.

The invention will be best understood by reference to the accompanying drawings 25 forming a part of this specification, and in which

Fig. 1 is a plan view of the invention;

Fig. 2 is an outer elevational view of the invention;

30 Fig. 3 is a vertical cross section thereof taken on line 3—3 of Fig. 2;

Fig. 4 is an enlarged fragmentary vertical section taken on line 4—4 of Fig. 1;

Fig. 5 is a fragmentary vertical view taken 35 on line 5—5 of Fig. 4;

Fig. 6 is an enlarged vertical section taken on line 6—6 of Fig. 3;

Fig. 7 is a fragmentary section taken on line 7—7 of Fig. 2;

40 Fig. 8 is an enlarged detailed section taken on line 8—8 of Fig. 5, and

Fig. 9 is a view of the fastening strap with the swivel adjusting means thereon, as also shown in Fig. 7.

45 The preferred form of construction, as illustrated in the drawings comprises an inner form casing or shell "I" and an outer form casing or shell "E," which in the construction of a chimney are arranged concentrically, as shown. The inner form part or shell "I" includes a plurality of flexible sheet metal plates 12 placed adjoiningly at their side edges. Vertical reenforcing or 50 stiffening bars 13 are secured to the outer sides of said plates, preferably three bars

being used on each plate. Each bar is provided with an upper offset portion 14 and a similar lower offset portion 15, and a band portion or member 16 is secured between each plate 12 and the offset portions 14 of 60 the bars 13 thereon. This member 16 is adapted to receive and hold the lower end of the next form plate placed above the plate 12. Openings or slots 17 are provided in the upper edge of each band 16 and extend 65 to the plate 12, to permit the surplus moisture and impurities or latents to drain off from the top of the concrete which is filled to the upper edge of said band members 16 and which is permitted to stand and harden. 70 These slots 17 are also adapted for passing tie rods 18 therethrough which extend from the vertical tie rods in the concrete inward to be attached to the scaffold posts for retaining the scaffolds firmly in position, and said 75 rods may be retained in the slots when the succeeding plates are placed in position above the present plates 12 and inward of the bands 16. (See Fig. 1.)

The means provided for holding the plates 80 of the inner shell in position includes a plurality of hooks or members 19 secured on bars 13 with suitable bolts, and a plurality of rods 20 clamped and retained in said hooks, each rod being preferably continuous 85 and laid or extended a plurality of times around said shell. The inner diameter of such a chimney is usually uniform throughout, but when it varies or tapers upwardly, then one or more pair of the plates are 90 slightly overlapped to provide for such taper, such overlapping being conveniently accomplished and the slight ridge of the concrete produced thereby being imperceptible 95 since the plates are thin and flexible.

The outer form means or shell E includes a plurality of flexible sheet metal plates 22 which are joined at their longitudinal edges, and vertical stiffening or re-enforcing bars 23, made preferably in the form of T-bars, 100 are mounted on the outer sides of said plates, and are preferably secured to and overlap the joining edges of the adjacent plates for completely closing the joints, as best shown in Fig. 5. Said bars are preferably secured to the plates by means of screw bolts 24, and the bolt holes in said bars are countersunk to receive corresponding depressed portions 105 of the plates, so that when the bars and bolts are drawn and tightened in position by 110

means of said bolts, that the inner surfaces of such plates for engaging the concrete are smooth and even. The bars 13 are similarly fastened to the plates 12 of the inner shell 5 with screws 24 and countersinks and depressed portions 25 on said plates, as shown in Fig. 6.

As the outer shell E is moved upward to form a narrower or contracted part of the 10 structure, the joined edges of two or more of the thin flexible plates are placed in overlapping position, as shown at 26 in Fig. 7, the corresponding re-enforcing bar 23 being first removed from said connected edges. The 15 plates are drawn and held together by means of straps or members 27 fastened with the outer end with bolts 28 on bars 23, said straps having angle members 29 at the outer ends, and a rod consisting of two swivelled 20 parts 30 is extended through the angle members 29 and provided with nuts 31 for drawing and adjusting said straps and thereby said plates into proper position around the outer upper edge of the last made section 25 of the chimney or other structure. Rod 30 is swivelled in order that it may move outward at the middle part so that said part need not press inward or possibly buckle the underlying plate 22 when the curvature 30 of said flexible plate is increased due to the decreased diameter of the chimney or similar structure.

Means is provided for readily lifting the outer shell E into a new elevated position 35 and for accurately drawing and adjusting the upper end of the shell in such new position. This means comprises a frame or diaphragm which, for constructing a chimney, includes an inner annular member or ring 32 and an outer annular member or ring 33 concentric with said inner member, both being preferably formed of overlapping sections of angle irons, as shown. Crossbars 34 are provided with plates 35 40 and 35' on their downturned ends and are secured with said plates to the inner and outer ring members 32 and 33 respectively, by means of suitable bolts, as best shown in Figs. 4 and 5. A threaded 45 rod 36 is mounted for rotation in said plates and ring members, and is held against longitudinal movement therein by means of nuts or members 37 and 38 which are secured to rod 36 with pins or in any suitable manner. A hanger 39 is mounted with a yoke 40 on the cross bar 34 and a roller 41 is mounted 50 in said yoke for readily moving said hanger on bar 34. The lower end 42 of said hanger is bent to embrace a band or member 43 fastened with a block 44 on the upper end 55 of plate 22, and a roller 45 is mounted in end 42 for engaging band 43 and readily moving thereon. The bands 43 and blocks 44 provide offset means on the ends of the 60 plates 22 whereby said frame including the 65 plates 22

hanger is adapted to raise the plates forming the outer shell, into the new position. Said frames are raised and supported by means of a suitable derrick mounted on a suitable support erected within the interior of the chimney, as is generally employed in this form of construction. A suitable hand crank 46 is also provided for engaging the angular ends 36' of rods 36 to rotate 70 said rods and thereby move and adjust the hangers 39 longitudinally on bars 34 and draw and adjust the plates 22 of the outer shell into proper position.

Two inner shell sections "I" and one such exterior shell "E" are usually employed, as indicated in Fig. 3, for constructing a section of concrete which is permitted to stand and harden, whereupon the sections are moved upwardly by means of the suitable derrick usually employed, the outer shell being moved directly upwardly, and adjusted by means of crank 46, while the rods 20 of the lower section of the inner shell are loosened and the plates of said lower section moved upwardly into position on the upper section and tightened by again applying the rods 20, whereupon said section is filled and then the preceding upper section of said shell has its rods 20 released and the plates thereof also moved upwardly in position and the rods 20 fastened in the hooks 19. This construction thus providing an efficient form which is readily moved and is accurately adjustable for erecting a chimney or similar construction.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A concrete form comprising a plurality of plates provided with upper bands having openings at the top edges for draining moisture and latents from the top of the concrete, and means for mounting and holding said plates in position.

2. A concrete form comprising a form member or shell, means at the upper end of said shell for engaging a superposed form member, said means being provided with slots in the top edge for draining latents therefrom and for extending tie rods therethrough.

3. A concrete form comprising a plurality of plates, members at the upper ends of said plates for receiving similar plates superposed on the first plates, said members having

- slots at the upper edges for draining surplus moisture and latents from the top of the concrete and also arranged for extending tie rods therethrough below the superposed 5 plates.
4. A concrete form comprising a plurality of plates, reenforcing bars on said plates, bands mounted between the upper offset ends of said bars and said plates for receiving 10 similar plates of the succeeding form, said bands having slots at the upper edges for draining latents and surplus moisture from the top of the concrete and for receiving tie rods therethrough.
5. A concrete form comprising a plurality of resilient plates, reenforcing bars secured longitudinally on said plates, supporting and clamping hooks on said bars, and a continuous rod clamped and held firmly in position 15 in said hooks and extending a plurality of times overlapped along said plates.
6. A concrete form comprising a plurality of resilient plates, reenforcing bars with offset portions at the top and bottom, bands 20 with slots mounted in some of said offset portions and secured to said portions and plates, said bands being adapted to receive and hold similar plates of the next succeeding form, supporting hooks mounted on said bars, and continuous rods clamped in said hooks each extending a plurality of times 25 around said plates.
7. A concrete form comprising a shell, means offset laterally from said shell, a frame provided with means for supporting and moving said offset means, and means 30 connected with said supporting means for accurately adjusting said shell.
8. A concrete form comprising a shell, means offset laterally from said shell, a frame provided with means for supporting and moving said offset means, and a threaded member operating on said supporting 35 means for accurately adjusting the same and said shell.
9. A concrete form comprising a shell, means offset transversely from said shell, a frame, hangers on said frame, and rollers on said hangers engaging said offset means.
10. A concrete form comprising a shell with offset means on said shell, a frame, hangers with rollers movably mounted on said frame, and rollers on said hangers to movably engage said offset means.
11. A concrete form comprising a shell with offset means on said shell, a frame, hangers with rollers movably mounted on said frame, rollers on said hangers to movably engage said offset means, and means 55 for accurately adjusting said hangers and shell.
12. A concrete form comprising a shell including a plurality of separable plates, means offset laterally from each plate, a frame, a hanger movable on said frame, 60
- means on said hanger to engage and readily move the same along said offset means, and a member having threaded engagement with said hanger for moving and accurately adjusting said hanger and plate. 70
13. A concrete form comprising a shell provided with means offset laterally therefrom, a frame provided with hangers adjustably mounted thereon and having means for engaging said offset means and to lift and support said shell, and means movably engaging said frame and said hangers for accurately adjusting the hangers. 75
14. A concrete form comprising a shell provided with offset means, a frame including cross bars, hangers movably mounted on said bars, means on said hangers including rollers for engaging said offset means to lift 80 said shell.
15. A concrete form comprising a shell including a plurality of separable plates, means offset radially from each plate, a frame including radially extending bars, a hanger movably mounted on each bar, means rotatably mounted in each hanger for engaging under the offset means on said plate to lift the same. 85
16. A concrete form comprising a shell with radial offset means, a holding frame including an inner and an outer member, cross bars connected to said members, members travelling on said bars and having means for engaging said offset means, and means extending through said frame members for accurately adjusting said shell. 90
17. A concrete form comprising a shell with offset means, a frame including an inner and an outer member, cross bars connected to said inner and outer members, hangers travelling on said bars and having means for engaging said offset means, and members mounted for rotation but against longitudinal movement in both of said frame members for accurately adjusting said shell. 95
18. A concrete form comprising a shell provided with radially offset means, a frame including an inner and an outer member, cross bars secured to said inner and outer members, hangers provided with rollers for travelling on said bars means including 100 rollers on said hangers for engaging and movably supporting said offset means, and a threaded rod extending through said frame members and the connected parts of said cross bar for accurately adjusting said hangers and shell. 110
19. A concrete form comprising a shell including a plurality of flexible sheet metal plates, reenforcing bars mounted over the joining edges of said plates, straps connected to pairs of reenforcing bars, swivelled rod means connected to said straps for drawing the plates together, offset means on the upper ends of the plates, a frame with supporting means for engaging said offset means 115 125 130

and to lift and support said plates, and means on said frame for accurately adjusting said lifting means and plates.

20. A concrete form comprising a shell including a plurality of flexible plates, reinforcing bars mounted over the joining edges of said plates, straps connected to the lower parts of several of said bars, swivelled rod means connected to said straps for drawing and holding the plates together, offset means on the upper ends of the plates, a frame including an inner and an outer member, cross bars connected to said frame mem-

bers, means movably mounted on said cross bars for supporting and moving said plates, and threaded means on said frame members for accurately adjusting said supporting means and therewith said plates.

In testimony whereof I have signed my name to this specification in the presence of 20 two subscribing witnesses.

MARTIN STIELER.
